(57) **CLAIM**

We claim the ornamental design for the button for rear view mirror assembly, as shown and described.

DESCRIPTION

FIG. 1 is a front perspective view of a button for rear view mirror assembly embodying a third embodiment of the present invention;

FIG. 2 is a front view thereof;

FIG. 3 is a left side view thereof;

FIG. 4 is a right side view thereof; and,

FIG. 5 is a bottom view thereof.

The broken lines in FIGS. 1-5 are to show the environment of the present invention, but do not form a part of the claimed design.
